ASSO. ATTORNEY

UNITED STATES PATENT OFFICE.

MANFRED BRANDENSTEIN, OF SAN FRANCISCO, CALIFORNIA.

SHEET-METAL RECEPTACLE.

1,290,061.

Specification of Letters Patent.

Patented Jan. 7, 1919.

Application filed September 27, 1916. Serial No. 122,395.

To all whom it may concern:

Be it known that I, MANFRED BRANDENSTEIN, a citizen of the United States, and a resident of the city and county of San Francisco, State of California, have invented a certain new and useful Sheet-Metal Receptacle, of which the following is a specification.

The invention relates to sheet metal receptacles and particularly to hermetically sealed cans.

An object of the invention is to provide an easily opened air tight receptacle.

Another object of the invention is to provide an easily opened air tight sheet metal receptacle having a friction cover with which the receptacle may be securely closed after its initial opening.

The invention possesses other advantageous features, some of which, with the foregoing, will be set forth at length in the following description, where I shall outline in full that form of the invention which I have selected for illustration in the drawing accompanying and forming part of the present specification. In said drawing I have shown one specific form of my invention, but it is to be understood that I do not limit myself to such form, because the invention, as expressed in the succeeding claims, may be embodied in a plurality of forms.

The drawing is an elevation of the receptacle of my invention, half in section, part thereof being broken away to reduce the size of the figure.

The receptacle is adapted to be used for hermetically containing food products and particularly food products such as coffee, which produce a pressure within the receptacle. The receptacle comprises a body portion 2 having on its open end an outwardly turned bead 3, which presents a smooth edge at the open end of the can. Seated in the body and preferably having its upstanding marginal portion 4 in frictional contact with the can body is a cover 5, the upstanding marginal portion of which is provided on its edge with an inwardly turned bead 6. The upper portion or neck of the can body and the marginal portion 4 of the cover are parallel to each other and preferably parallel to the axis of the body, so that the cover may be held in place by frictional engagement.

Between the cover and the can body there

is arranged a gasket 7 of suitable conformable material and the can body is formed to provide a seat for the gasket, preferably by rolling the groove 8 in the body. When the cover has been pressed into engagement with the gasket, the beads 3 and 6 preferably occur in the same horizontal plane. The cover is fastened to the can body by a fastening member 9 of soft sheet metal, which embraces the beads and which is in tight engagement therewith. This fastening member is rolled or pressed over the beads and when in place is of channel shape and acts to lock the cover to the can body, and is preferably provided with a tongue 12, by which it may be grasped when it is desired to remove the fastening member. The beads not only obviate any sharp edges, but also form enlargements which are engaged by the fastening member and the bead on the friction cover also serves the further advantage of providing a grip whereby the friction cover can be removed. Some classes of food products, such as coffee, are not removed entirely from the can when it is first opened and by providing the friction cover, the coffee remaining in the can may be retained in excellent condition.

I claim:

1. An easily opened air tight receptacle comprising a body portion having an upstanding neck provided with an outwardly turned bead at its upper edge, a cover having an upstanding marginal portion in frictional contact with said neck and provided with an inwardly turned bead at its upper edge, said beads lying in substantially the same horizontal plane, and a soft sheet metal fastening member embracing said beads.

2. An easily opened air tight receptacle comprising a body portion having an outwardly turned bead at its upper edge and provided with a seat for a gasket below said edge, a gasket, a cover engaging said gasket and having an upstanding marginal portion in frictional contact with said body, an inwardly turned bead at the upper edge of said marginal portion, said beads lying in substantially the same horizontal plane, and a readily removable fastening member embracing said beads.

3. An easily opened air tight receptacle comprising two vertical sheet metal parts arranged in contact, one of said parts embodying the body and the other the cover,

said parts being provided on their upper edges with oppositely turned beads lying in the same horizontal plane and adjacent each other and a readily removable sheet metal strip embracing said beads, the edges of said strip lying in the same horizontal plane and being pressed horizontally toward each other to snugly engage said beads.

In testimony whereof, I have heretunto set my hand at San Francisco, California, this 10 23rd day of September, 1916.

MANFRED BRANDENSTEIN.

In presence of—

J. B. GARDNER,

MARGUERITE S. BRUNER.
